CARPET.

No 17,742.

Patented Sept. 27, 1887.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 17,742, dated September 27, 1887.

Application filed July 21, 1887. Serial No. 944,043. Term of patent 3½ years.

To all whom it may concern:

Be it known that I, OTTO HEINIGKE, of New Utrecht, Long Island, New York, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The characteristic feature of my design is the figure A, which is repeated continuously

over the face of the carpet. The figure A is a double-key-shaped figure, substantially square in its exterior outline, with its corners beveled. In the spaces formed in this way at the 20 corners are small ornamental figures. The figure A is repeated at regular intervals over the face of the design.

What I claim as new, and desire to secure by Letters Patent, is—

25 The design for carpets, consisting of the design substantially as shown.

OTTO HEINIGKE.
